BUMPER

Robert J. Scheelk, Oak Park, Mich., assignor to General Motors Corporation, Detroit, Mich., a corporation of Delaware

Application December 22, 1955, Serial No. 39,435

Term of patent 7 years

(Cl. D14—6)

Figure 1 is a top plan view of a bumper showing my new design;

Figure 2 is a front elevational view of the bumper of Figure 1;

Figure 3 is a side elevational view of the bumper of Figure 1;

Figure 4 is a sectional view taken on the plane indicated by line 4-4 of Figure 2;

Figure 5 is a sectional view taken on the plane indicated by line 5-5 of Figure 2; and

Figure 6 is a sectional view taken on the plane indicated by line 6-6 of Figure 2.

The dominant features of my design reside in the full line portions of the drawing.

I claim:

The ornamental design for a bumper, substantially as shown and described.
